UNITED STATES PATENT OFFICE.

WILLIAM G. KACHEL, OF MINNEAPOLIS, MINNESOTA.

AUTOMATIC STOP FOR GOVERNORS.

SPECIFICATION forming part of Letters Patent No. 715,481, dated December 9, 1902.

Application filed March 28, 1902. Serial No. 100,357. (No model.)

To all whom it may concern:

Be it known that I, WILLIAM G. KACHEL, of Minneapolis, Hennepin county, Minnesota, have invented certain new and useful Im-
5 provements in Automatic Stops for Steam-
Governors, of which the following is a speci-
fication.

The invention relates to attachments for steam-engines, particularly those of the Cor-
10 liss type, where the governor-stem is connected with the governor-cams, whose movement con-
trols the steam-supply valves and the opera-
tion of the engine. If the governor-stem
drops to its lowest position, steam will be cut
15 off entirely from the cylinder, and it will be
necessary to raise the stem before the engine
can be started. It has been customary here-
tofore to wedge or plug the stem to prevent
20 its dropping far enough to entirely cut off the
supply of steam to the cylinder. This method
of limiting the downward movement of the
stem has been found inconvenient and is some-
25 times forgotten in the haste of shutting down
the engine; and the object, therefore, of my
invention is to provide means in connection
with the main steam-supply-pipe valve for
automatically locking the stem in its raised
30 position when the valve is being closed and
releasing the stem when the valve is open.

35 The invention consists generally in a piv-
oted latch adapted to engage a shoulder or
lug on the governor-stem and means con-
trolled by the movement of the steam-supply
valve for automatically actuating said latch
40 to move it into the path of said lug or with-
draw it therefrom.

Further, the invention consists in various
constructions and combinations, all as here-
inafter described, and particularly pointed
45 out in the claims.

In the accompanying drawings, forming
part of this specification, Figure 1 is a plan
view of a globe steam-supply valve with the
governor-stem shown in section and my in-
45 vention applied thereto. Fig. 2 is a side ele-
vation of the same. Fig. 3 is a detail of the
governor, showing the lug on the stem and
the pivoted latch. Figs. 4 and 5 are details
50 of the part of the mechanism that engages the
steam-supply valve. Fig. 6 is a detail of a
portion of the device employed in connection

with a gate-valve. Fig. 7 is an end view of
the same.

In the drawings, 2 represents a steam-gov-
ernor casing having vertical slots 3 and a 55
stem 4, whereon the usual centrifugal gov-
ernor-balls 5 are supported. The stem is con-
nected with the governor-cams in the type of
engine above referred to, and the movement
of these cams controls the supply of steam to 60
the cylinder. Should the stem be allowed to
drop to its lowest position, steam will be en-
tirely cut off, and it will be necessary to raise
the governor before starting the engine.

As above referred to, it has been customary 65
to wedge or plug the governor before starting
the engine to limit the downward movement
of the stem; but it has been found inconven-
ient, and I prefer to provide means for auto-
matically locking and releasing the governor 70
when the main steam-supply valve is oper-
ated to stop or start the engine. With this
end in view I provide lugs 5 on the governor-
stem that are vertically slidable in the slots
3 and act as guides for said stem, and near 75
the lower end of said slots I pivot a latch 6,
to which a rod 7 is pivotally connected at one
end, its opposite end being slidable in a guide
8 on the globe steam-supply valve 9. Upon
the stem 10 of this valve I secure a block 80
11, having an inclined or beveled face 12,
that is adapted to engage the end of the rod
7 and move the same lengthwise while the
stem is being revolved to close the valve.
This movement of the rod swings the latch 6 85
to the vertical position, (indicated by dotted
lines in Fig. 2,) where its end will be in the
path of the lug 5 and limit the downward
movement of the governor-stem. The posi-
tion of the latch and of the lug is determined 90
by experiment, so that downward movement
of the governor will be arrested before the
steam-supply is entirely cut off. During the
lengthwise movement of the rod 7 a spring
13, provided on said rod between the guide 8 95
and a pin 14, will be compressed, so that when
the valve is opened and the end of the rod
slides down the inclined surface the tension
of the spring will be sufficient to return the
rod to its normal position and draw the latch 100
to one side out of the path of the lug on the
governor-stem. In this way a perfect auto-

matic stop is provided that is positive in its action, being controlled wholly by the movement of the steam-supply valve, and so simple in construction that it cannot possibly be 5 come inoperative through the disorder of any of its parts or connections.

In Fig. 2 I have shown a gate-valve 15, having a threaded stem 16, whereon the member 11 is loosely arranged, and provided with a 10 longitudinal groove 17, that is adapted to receive the end of the rod 7. In this form of valve when the stem is rotated the block 11 will be held from turning by the rod, the end of which traveling in the groove will cause 15 lengthwise movement thereof and consequent oscillation of the locking-latch.

I am aware that various devices and attachments may be provided for operating the pivoted latch by the movement of the main 20 steam-supply valve; but I regard such changes as mere modifications that would suggest themselves to any one skilled in the art.

I claim as my invention—

1. The combination, with a centrifugal 25 steam-engine governor having a stem provided with a suitable stop, of a pivoted latch adapted to engage said stop and limit the downward movement of said stem, and means controlled by the movement of the main 30 steam-supply valve for automatically moving said latch into the path of said stop and withdrawing the same therefrom when said valve is being operated to stop and start the engine.

2. The combination, with a centrifugal 35 steam-governor stem, of a pivoted latch adapted to engage said stem and limit the downward movement of the same, a rod pivotally connected with said latch, a steam-supply valve, a block provided on the stem of said

valve and having an inclined surface to engage the end of said rod, to move the same lengthwise and oscillate said latch to swing it into the path of said stem when said valve is being closed, and a spring provided in connection with said rod for automatically withdrawing said latch from the path of said stem when the valve is being opened.

3. The combination, with a centrifugal steam-governor stem, of a stop provided in the path of said stem and adapted to limit the downward movement of the same, and suitable connections provided between said stop and the main steam-supply valve for automatically operating said stop to move it into the path of said stem or withdraw it therefrom accordingly as said valve is being closed or opened.

4. The combination, with a centrifugal steam-governor stem, of a stop device adapted to limit the downward movement of said stem, 60 a rod connected with said stop device, a guide wherein said rod is slidable, a steam-supply valve, an inclined or beveled surface provided on the stem of said valve and adapted to engage the end of said rod to move the 65 same lengthwise and actuate said stop device when the valve is being closed, and a spring device provided on said rod and adapted to return said stop device and said rod to their normal position when said inclined surface is 70 moved out of engagement with said rod by the opening of said valves.

In witness whereof I have hereunto set my hand this 25th day of March, 1902.

WILLIAM G. KACHEL.
In presence of—
RICHARD PAUL,
M. C. NOONAN.
